UNITED STATES PATENT OFFICE.

CHARLES ELBRIDGE GIBBS, OF ORANGE, MASSACHUSETTS.

WATER-WHEEL GOVERNOR.

SPECIFICATION forming part of Letters Patent No. 307,753, dated November 11, 1884.

Application filed May 20, 1884. (No model.)

To all whom it may concern:

Be it known that I, CHARLES ELBRIDGE GIBBS, of Orange, in the county of Franklin, of the Commonwealth of Massachusetts, have 5 invented a new and useful Improvement in Water-Wheel Governors; and I do hereby declare the same to be described in the following specification and represented in the accompanying drawings, of which—

10 Figure 1 is a top view, Fig. 2 an end elevation, Fig. 3 a front elevation, and Fig. 4 a vertical median and transverse section, of a governor containing my invention, the nature of which is defined in the claims hereinafter presented. Fig. 5 is a vertical section of the machine taken through the main shaft longitudinally thereof. Figs. 6 and 7 are herein-after described.

In the said drawings, the frame for supporting the main operative parts of the machine is shown at A, there being arranged within it, as shown, and supported in suitable boxes a a, the main shaft B.

Fixed on a tubular shaft, C, fitted to revolve 25 on the main shaft B, there are a driving wheel or pulley, D, and a spur-gear, e. The said gear e engages with another and longer gear, d, fixed on another shaft, E, arranged as represented, and supported in boxes e e. There 30 are to the shaft two eccentrics, f f, which stand in opposite directions relatively to each other. The arms g g of the collars h h of the said eccentrics are pivoted to two vibratory arms, F F, that turn on the main shaft B, near the 35 outer sides of two gears, G G, fixed on such shaft.

To each arm F there are two pawls, h', to engage with the next adjacent gear G, there being between the two gears a sector, H, that 40 turns loosely on the shaft B, and by a bar, i, jointed to it is connected to the yoke k, that embraces the sleeve l, adapted to slide vertically on an upright shaft, I. To a cross-head, m, fixed to the said shaft and to the sleeve l, 45 there are jointed two sets of toggles or arms, n n, each set at their connecting joint being provided with balls or weights o o, as shown. The said shaft I, cross-head m, sleeve l, two sets of arms n, and their weights are what is 50 usually termed a "ball-governor."

On the shaft I there is fixed a bevel-gear, p,

to engage with another such gear, q, carried by the shaft E. The driving-pulley being revolved by an endless belt proceeding from a pulley and the main or some other proper 55 shaft of a mill, the ball-governor will be revolved, the motion of the said governor being accelerated as that of the pulley may be increased. As the velocity of revolution of the governor may increase, its balls or weights by 60 centrifugal force generated in them will be thrown outward from their vertical shaft I, and thereby will cause the aforesaid yoke to be raised on the said shaft, whereby the sector H will be moved upward. The two sets 65 of pawls in the meantime will be reciprocated in opposite directions on the periphery of the arc of the sector. As the work to be done by the water-wheel may increase, the gate of such wheel has to be opened more, the contrary 70 taking place as the work to be done by the said wheel may decrease.

The shaft B is to be properly applied to the gate by suitable gears or mechanism, such as will cause the gate to be raised when the said 75 shaft is revolved one way, and depressed while the shaft may be turned in the opposite direction.

As the speed of rotation of the governor may increase, the sector will be raised to cause 80 the pawls in passing off it to turn the two gears G G in a direction to effect a downward or closing movement of the gate. So, as the speed of rotation of the governor may decrease, a contrary result will follow—that is, 85 the gate will be raised.

A water-wheel governor as hereinbefore described is not my invention, it being well known and in common use, and generally termed the "Schofield Governor."

In carrying out my said invention I have combined with such a governor, first, a "stop-motion;" second, a friction wheel and brake and its clamping-screw, and, third, a lever and a weight adjustable thereon, said additions and the objects of them being thus described: The friction-wheel is shown at K as fixed on the shaft B concentrically and clasped peripherally by the brake L. This brake is in two separate parts, r and s, formed as shown, 95 and pivoted at one end of each to the frame A. A screw, t, goes through one of such

parts near its free end and screws into the other. On turning such screw one way the two parts of the brake will be drawn toward the wheel, so as to hold with friction the shaft 5 from being by the weight of the gate turned backward during the retreat of either set of pawls on the sector. The screw of the brake is to be set up just sufficiently to prevent, by means of the friction wheel and brake, the 10 gate from falling, so as to turn the shaft in a manner to revolve its gears while either set of the pawls may be in retreat on the sector, as it will not do to have any back movement or "backlash" of the shaft during such retreat of the pawls.

The next part of the machine to be described is the stop-motion.

On the gate being fully open it becomes necessary to prevent the governor from acting to raise it higher; otherwise breakage of the governor or the gate or parts of the mechanism for operating the gate would be liable to result. To this end I have the stop-motion, which is a mechanism that on the gate being 25 fully open will cause the sector to be raised into its median position, so that the sets of pawls will by it be held out of action on the gears G G, while such sets of pawls may be reciprocated on the sector. An auxiliary sector, M, having its periphery notched or provided with a shoulder, as shown at *u* in Fig. 6, which is an under side view of such sector, extends downward from the hub of the sector H. Below the two gear-wheels G G 35 is a horizontal shaft, N, having on one end of it a gear, *v*, to engage with a gear, *w*, fixed on the shaft B. The shaft N consequently derives its rotary motion from the shaft B through the two gears *v* and *w*. The 40 shaft N is screw-threaded, as shown at *x*, and has on the screw a nut, *y*, suitably formed and adapted to a rail, *z*, to slide thereon rectilinearly and longitudinally thereof. A front view of this nut is shown in Fig. 7. There is 45 fulcrumed on the shaft N a bent lever, O, whose shorter arm, *a'*, extends into the notch *u* of the sector M. A pin, *b'*, adapted to the lever to slide transversely through it, bears at one end against the inner face of the nut *y*, and is 50 forced up to such by a spiral spring, *c'*, encompassing the pin, and fastened to it and the lever. Furthermore, near the other end of the said pin *b'* there projects from the shaft N an arm or dog, P. As the gate may rise the 55 shaft N will be put in revolution in a manner to cause the screw *x* to move the nut *y* forward on the rail *z*. In so advancing, the nut will force the pin *b'* endwise toward the dog

P until such dog, which will revolve with the shaft N, may be caused to be forced against 60 the side of the pin. On this taking place the dog by its action on the pin will press it upward, and thereby create a movement of the lever O such as will cause it by its action against the notched sector to move the latter 65 to force the sector H up into its median position, in which ease the two sets of pawls in reciprocating on such sector will not act on the wheels G G to revolve them. Thus it will be seen that with the stop-motion the shaft B 70 will be stopped in its rotary motion on the gate being open to its extreme. Should the speed of the governor increase, the sector H will be moved so as to enable the pawls to turn the gears in a manner to effect a downward movement of the gate. A lever, R, fulcrumed to a post, S, and having its shorter arm pivoted to the yoke of the ball-governor, has its longer arm provided with a weight, T, adjustable lengthwise on it. The purpose of 80 this lever and weight is to counterbalance or overcome more or less the gravitating power of the weights of the governor, in order to cause such weights to move outwardly quicker by centrifugal force as the speed of the main 85 shaft of the mill may require from time to time.

I claim—

1. The combination of the water-wheel governor, substantially as described, and a friction-wheel applied on its main shaft, with a 90 brake and its clamping-screw adapted to such wheel and to the frame of the said governor, and to operate with the wheel essentially and for the purpose as set forth.

2. The combination of the water-wheel governor, substantially as described, with a stop-motion, essentially as represented, applied to the frame main shaft, and notched sector of 100 said governor, such stop-motion consisting of the gears *v* *w*, shaft N, and its screw *x* and dog P, the nut *y* and its supporting-rail *z*, the pin *b'* and the spring *c'*, and the bent lever O and notched sector M, arranged and applied as represented.

3. The combination substantially as described, constituting the water-wheel stop-motion, it consisting of the gears *v* and *w*, shaft N, screw *x*, dog P, nut *y*, rail *z*, pin *b'*, spring *c'*, bent lever O, and notched sector M, 110 arranged and applied essentially as set forth.

CHARLES ELBRIDGE GIBBS.
